PORTABLE SIGN FRAME

Charles H. Lush, Riverhead, N. Y.

Application January 20, 1932, Serial No. 587,815

10 Claims. (Cl. 40—125)

The present invention relates to certain improvements in portable frames for signs.

The principal object of the present invention is to provide a portable frame for a sign that can be cheaply manufactured and one having a minimum number of parts.

It is a further object of the invention to provide a portable sign frame constructed in a manner to permit the maintaining of the frame in upright position while readily allowing the insertion and withdrawal of the sign plate from the frame.

With these and other objects and purposes which will be in part obvious and in part pointed out hereinafter, the invention consists in the construction, arrangement and combination of the various parts of my apparatus, whereby the objects contemplated are attained as hereinafter more fully and particularly set forth, pointed out in the claims and illustrated in the accompanying drawings, in which

Fig. 1 is a perspective view of the new and improved portable sign frame.

Fig. 2 is a view partly in cross section disclosing the manner in which the bottom member is cut away or grooved to permit the insertion of the sign.

Fig. 3 is a perspective view of the base plates.

Fig. 4 is a perspective view of the legs of the frame and the plate for maintaining the sign within the frame.

Fig. 5 is an end view of the portable frame.

Fig. 6 is a modified form of the device.

Fig. 7 is a partial elevational view of one of the legs used in the modified form.

Fig. 8 is a plan view partly in section of a further modified form.

Fig. 9 is a view taken on line 9—9 of Fig. 8.

Fig. 10 is a partial section taken on line 10—10 of Fig. 8.

Fig. 11 is a partial perspective view of one of the supporting members and the base member, and

Fig. 12 is a partial perspective view of the bracket and the side member attached thereto.

Referring to the drawings, in which like reference characters indicate like parts, the numeral 10 indicates the frame of what is known as the portable sign. The frame 10 may be formed from round or square open seam tubing or metal formed to represent molding, although it is to be understood that other materials could be used without departing from the spirit of the invention.

55 The frame 10 is provided with channelled side

members 11 and 12 and a channelled top member 13. The base portion of the frame indicated at 14 is cut away or grooved at 15 to allow for the insertion of the sign 16.

The frame is disclosed as being stamped from a single sheet of metal or the like, although it is to be understood that the top, sides and bottom members can be separate and welded or otherwise secured together.

This frame is to be used in what is commonly 10 called a side-walk sign and so there is provided supporting members 17 for maintaining the frame in an upright position while being displayed. The supporting members or legs 17 are made from 15 steel stampings in the form of a channel as illustrated in Figure 4 of the drawings, and have their ends which contact with the ground or the like, bevelled as at 18.

For securing the legs 17 to the frame 10 there is provided base or supporting plates 19 which 20 are welded or otherwise secured to the frame. The base plates serve also to form a brace for the sign. The base plates 19 have depending flanges 20 through which rivets or bolts 21 are 25 adapted to pass for retaining the leg members 17. Figure 3 clearly illustrates the construction of the base plates. It will be noted that these plates are channelled at 22 to fit the contour of the side members 11 and 12 and have flanges 23 and 24 to which the bottom portion 14 is welded.

For retaining the sign within the frame and also forming an additional support for the leg members 17, there is provided a channel member 25 having slots 26 therein. The channel member 25 is secured to the legs 17 in the following manner. The channel member 25 is placed within one of the channel legs 17 and the bolt or rivet 21 is passed through the base plate 19 and through the slots 26 of the channel member 25. This is accomplished when the legs are 30 in the position illustrated in dotted lines in Figure 5. When the legs are positioned as illustrated in full lines in Figure 5, the member 25

35 slides forward the extent of the slot and the notches 27 slide over the bolt or rivet of the opposing leg. Should it be necessary, a screw-driver or some round pointed piece of metal may be used to force the notches in place over the bolt or rivet. When the member 25 is in position the legs are automatically locked and the sign inserted 40 in the frame is firmly retained in position since the channel insert members 25 close each end of the frame that has been cut out.

45 Referring to Figure 6 there is disclosed a modified form in which the channel insert member 25 50

is dispensed with. In this form the side members 11 and 12 are provided with spring catches 28 which are engaged by specially constructed ends of the leg members 29. As illustrated in Figure 7, the leg members 29 are cut out at their hinged ends, as shown at 30, the object of which is to close the opening at the bottom of the frame, thereby holding the sign plate within the frame. It will be noted that as each leg member is swung down into its normal position, the end 30 will engage with the spring catches 28 in a manner to hold the sign plate within the frame. In other words, the cut-out portions of each leg member will be opposed, thereby providing sufficient area upon which the sign plate may rest to securely maintain the sign within the frame.

It is to be understood that the frames are completely assembled at the factory and are shipped with the legs elevated, as indicated by the dotted lines in Figure 5 of the drawings. It is merely necessary for the purchaser to insert the sign plate within the frame and force the legs downwardly into their normal position and lock them as described. The advantage of this feature is readily apparent.

Referring to the construction illustrated in Figures 8 to 12 inclusive there is illustrated a construction in which the base portion of the frame constitutes two separate bars welded to the supporting members. The numeral 10a indicates one of the sides of the frame. Welded or otherwise secured to the side 10a is a bracket 31 to which the legs or supporting members 17a are pivoted by means of bolts or rivets 21a. As above indicated, the base portion of the frame is made up of two bars 32 and 33. The bar 32 is welded at the inner ends of two of the legs and the bar 33 is welded at the ends of the other two legs. This forms a pair of U-shaped bottom frames which when in their closed position bring the two bars together to form retaining means for the sign, which, as in the preferred form illustrated in Figure 1 of the drawings, is positioned in the channel portions within the sides and top of the frame. The same locking means as illustrated in the preferred form is utilized in this modified construction. This locking means is indicated generally at 34 in the drawings. Reinforcing members 35 are also welded to the legs and to the bars 32 and 33.

As in the preferred form, it is to be understood that these frames are completely assembled at the factory. It is merely necessary for the purchaser to insert the sign in the channels within the sides and top of the frame. The legs are then forced downwardly and since the base portions and legs are integral, when the sign is in its set up position, the base bars will come together, thereby firmly retaining the sign within the frame. The legs are then locked in the manner described in the preferred form. This construction permits the purchaser to set up and display a sign rapidly and with a minimum amount of effort and time expended.

Various changes may be made in the construction and arrangement of the invention above set forth without departing from the real spirit and purpose thereof, and it is the intention to cover by the following claims all modified forms of structure or use of mechanical equivalence which

may be reasonably included within their scope.

I claim:—

1. A portable sign frame comprising channelled top and side members for receiving a sign, a bracket secured to each of said side members and supporting means pivotally secured to each side of said bracket members and retaining the sign within said frame. 5

2. A portable sign frame for receiving a sign plate comprising channelled top and side members, a grooved base member, base plates secured to the side and base members, channelled shaped legs secured to said base plates and a channelled shaped member secured within said legs for locking the same and retaining the sign plate within 15 the frame. 10

3. A portable sign frame for receiving a sign plate comprising channelled top and side members, base plates secured to said side members and a pair of U-shaped supporting frames secured to 20 said base plates assisting in retaining the sign within said frame. 20

4. A portable sign frame for receiving a sign plate comprising channelled top and side members, base plates secured to the side members and channelled-shaped leg members hinged to said base plates having a pair of base members forming the bottom of the frame secured thereto. 25

5. A portable sign frame for receiving a sign plate comprising channelled top and side members, base plates secured to the side members, channelled-shaped leg members hinged to said base plates, a pair of bars secured to said leg members forming the bottom of the frame and means for locking said leg members. 30

6. A sign frame comprising top and side members, means upon said top and side members for retaining a sign in alignment with said top and side members and pivoted means connected to said side members and folding upon each side 40 thereof for supporting the sign frame and for retaining the sign within said frame. 40

7. A portable sign frame for receiving a sign plate comprising top and side members, leg members hingedly supported from said side members 45 and members forming the bottom of the frame secured to said leg members. 45

8. A portable sign frame for receiving a sign plate comprising top and side members, leg members hingedly supported from said side members, 50 members forming the bottom of the frame secured to said leg members and means for locking said leg members in frame supporting position.

9. A portable sign frame for receiving a sign plate comprising top and side members, leg members hingedly supported from said side members, members forming the bottom of the frame secured to said leg members and sliding means for locking said leg members in frame supporting position. 55

10. A portable sign frame comprising top and side members for receiving a sign, a plate secured to each side member and supporting means for said sign frame hingedly secured to said plates upon each side of said side members so that when 65 in collapsed position said supporting means can fold against each side of said side members and means for retaining a sign in said frame. 60

CHARLES H. LUSH.
